UNITED STATES PATENT OFFICE.

EMIL EFRAN, OF BRÜNN, AUSTRIA-HUNGARY.

APPARATUS FOR CHARGING AND FEEDING FUEL TO STEAM-ENGINES.

SPECIFICATION forming part of Letters Patent No. 655,700, dated August 14, 1900.

Application filed December 9, 1899. Serial No. 739,805. (No model.)

To all whom it may concern:

Be it known that I, EMIL EFRAN, a subject of the Emperor of Austria-Hungary, and a resident of Brünn, Austria-Hungary, have 5 invented certain new and useful Improvements in Apparatus for Charging and Feeding Fuel to Steam-Engines, of which the following is a specification.

My present invention relates to improvements in apparatus for charging and feeding fuel to steam-engines, such as described and set forth in my prior United States application, Serial No. 700,055; and it consists in the construction and novel combination of parts, 15 fully described and claimed hereinafter.

In the accompanying drawings, Figure 1 is a front view of the improved apparatus. Fig. 2 is a side elevation thereof with parts shown in section. Fig. 3 is an enlarged view of a 20 movable fire-bar and the actuating connections. Figs. 4, 5, and 6 are enlarged detail views of the device for conveying fuel from the charging or filling funnel upon the grating. Figs. 7 and 8 show a modification hereinafter referred to.

Like letters refer to like parts throughout all the views.

The principal features of the invention consist in providing means for relieving the slides 30 from strain and imparting double movement to the fuel as the latter travels over the grating, which result is attained by actuating alternately the fire-bars of the latter, and devices whereby the fuel is easily conveyed from 35 the filling-funnel into the fire-box without crushing said fuel. The slides are relieved from strain and a double movement is imparted to the fuel on the fire-bars by forming small steps on said fire-bars and moving lon- 40 gitudinally each alternate fire-bar, the parts being arranged so that when the movable fire-bars are brought to their extreme front position the steps thereof are located in advance of the steps of the stationary fire-bars 45 to a distance of about the length of their stroke. Said steps produce at each stroke a conveyance or feeding of fuel, which is brought at the end of each stroke behind the steps of the stationary fire-bars, upon which 50 the fuel is retained when the movable bars are again moved forward.

The movement of the alternate fire-bars is

obtained as follows: The front ends of the movable fire-bars R^7 are hook-shaped and fitted over a shaft W , Figs. 1, 2, and 3, carrying wheels or rollers R^4 , running over suitable rails S , secured to the frame of the fire-box. The rear ends of said movable fire-bars rest on another shaft W' , arranged on the rear support R' . The movement of the shaft W 55 is obtained as follows: The hubs e^4 of the cams E and E' , Figs. 1, 2, and 3, actuating the slides S' , are arranged eccentrically and employed for actuating levers h^2 and h^4 , provided with longitudinal eyes A^2 A^4 , respectively, engaging said eccentric hubs, said levers being pivoted on pins z^2 , secured to the frame of the fire-box. The lower ends of said levers h^2 h^4 are pivotally connected with the 60 shaft W by means of connecting-rods S^2 S^3 . 70

It will be seen that each revolution of the motor-shaft W^2 produces a longitudinal movement of the fire-bars resting on the shafts W and W' to a distance corresponding to the double eccentricity of the hubs, whereby the 75 fuel is slowly carried away without preventing the same from burning, as would be the case when the fire-bars are moved vertically at the same time. The stationary fire-bars rest at their front ends on the support R and 80 at their rear ends on the support R' .

The fuel is fed from the filling or charging funnel to the grating by the following arrangement: Under said filling or charging funnel I arrange a carriage W^7 . The wheels R^3 R^5 run on the upper frame-plate P , Figs. 1, 2, 4, 5, and 6, the side and back walls of the funnel extending to the plate P of said carriage, while the front wall is terminated at 1 at a distance of about ten centimeters 90 above said plate P . When the carriage is in its extreme forward position, the plate P closes the lower opening of the funnel, and the front edge K of said plate extends to a certain distance from the front wall of the funnel, said 95 projecting plate portion being in accordance with the nature of the fuel and the quantities to be fed to the grating. This arrangement results in that the fuel is settled upon the carriage on a certain incline, and when the carriage is moved backward until the front edge thereof is in the plane of the front wall of the funnel the amount of fuel on the fore end of the carriage is caused to drop 100

through the aperture s' , provided in the plate P^3 , upon the incline P^5 , said fuel rolling then down before the feed-slides S' , pushing the fuel over the plate P^4 upon the grating. 5 When the fuel is located on the grating, it is submitted to the pressure from the slides and to the continuous action of the movable fire-bars. When the carriage is again moved forward, it carries with it the amount of fuel 10 settled on said carriage, while fresh fuel comes on the latter.

The motion of the carriage is obtained as follows: To the under side of the carriage-plate P are suitably secured two bars S^5 and 15 S^6 , Figs. 1, 4, 5, and 6, in the ends L of which are journaled the shafts of wheels $R^3 R^5$, and which are terminated by slide-heads $G' G^2$, respectively. Said slide-heads are provided with pins z' and z^3 , respectively, engaging 20 elongated eyes provided in levers $h' h^2$, pivoted on pins z^2 , already described, and the lower ends of which are provided with elongated eyes $A' A^3$, engaging cams $H' H^3$, keyed upon the drive-shaft W^2 for this purpose. It 25 will be seen that the rotation of said shaft imparts a reciprocating movement to the feed-carriage.

Instead of actuating the slides S' by means of the cams $E E^2$ and to cause the rods of 30 the slides to engage circular grooves in said cams I provide said rods B , Figs. 7 and 8, with elongated eyes a , embracing cams E^5 . The hub N , the side plate p , and the cam-disk E^5 are made integral with one another. 35 The side plate p is secured by means of screws s^2 , said plates $p p'$ serving to hold the rod-eye a in the vertical plane.

Instead of causing the slide-heads $G' G^2$ of the bars $S^5 S^6$ of the carriage W^7 to slide in 40 slots provided in the frame of the fire-box I

provide these heads with rollers running in said slots.

Having fully described my invention, what I claim, and desire to secure by Letters Patent, is—

1. In an apparatus of the class described, the combination with the longitudinally-movable and stationary fire-bars, and steps formed on the upper faces of said fire-bars, of the shaft W' supporting the rear ends of the 50 movable fire-bars, another revoluble shaft, supporting the front ends of the movable fire-bars, wheels on said shaft and running on suitable rails secured to the frame of the fire-box, levers $h^2 h^4$ pivotally connected with said 55 shaft and pivoted in pins z^2 , elongated eyes in said levers a drive-shaft and cams E, E^4 , keyed on the drive-shaft and the eccentric hubs e^4 of which are engaged by said elongated eyes, substantially as set forth. 60

2. In an apparatus of the class described the combination of the device for conveying fuel from the charging-funnel to the grating embodying the charging-funnel, a flat carriage the wheels of which run on the upper 65 plate P of the fire-box, a suitable aperture in the front wall of the charging-funnel, another aperture in the plate P , levers h', h^3 fulcrumed on pivots z^2 and pivotally connected with said carriage elongated eyes in the lower 70 ends of said levers a drive-shaft W^2 and cams H', H^3 keyed on the drive-shaft and engaged by said elongated eyes, substantially as set forth.

In testimony whereof I have hereunto set 75 my hand in presence of two witnesses.

EMIL EFRAN.
